UNITED STATES PATENT OFFICE.

WALTER S. GRAY, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed December 31, 1924. Serial No. 759,068.

This invention relates to improvements in kerf cutting mining machines and more particularly to machines of the type mounted permanently upon a wheeled support. The 5 principal object of the present invention is to provide a machine of the class described in which a cutter bar is pivotally supported for universal movement to cut kerfs varying in planes from the horizontal to the vertical. 10 A further object is to provide a machine of the class above set forth in which the cutter chain sprocket may be actuated in all permissible positions of the cutter arm by a power source which selectively controls also 15 certain of the cutter arm movements and mechanism for vertical adjustment of the entire apparatus with respect to the wheeled support.

The invention may be best understood by 20 reference to the accompanying drawings which illustrate one embodiment thereof. In these drawings:

Figure 1 is a side view of a machine constructed in accordance with my invention, 25 with parts broken away and shown in longitudinal cross section;

Figure 2 is a plan view of the machine shown in Figure 1;

Figure 3 is a longitudinal plan section 30 taken on line 3—3 of Figure 1 but drawn to a larger scale; and

Figure 4 is a front view of the machine shown in Figure 1 illustrating the manner in which the machine may be adjusted to cut 35 a kerf either in a horizontal or in a vertical plane with respect to the mine floor.

Referring now to details of the drawings, the machine includes a base frame 1 mounted on axles 2, 2, having supporting wheels 3, 3.

40 A turntable 5 provided with a central bearing 6 is mounted for rotatable movement on said base and is provided with a plurality of upright standards 4, 4, thereon. As herein shown these standards are mounted in

45 pairs spaced on opposite sides of the turntable between which is supported a sub-frame 7 carrying the cutting element of the machine. As shown herein the sub-frame is vertically adjustable with respect to the up-

rights 4, 4. This adjustment is provided by means of a plurality of pinions 8, 8, carried on upright arms 9, 9 of frame 7 and engaging racks 10, 10 on the upright supports 4, 4. Actuating mechanism for said pinions will 55 hereinafter be described.

The cutting element comprises a cutter arm 15 projecting forwardly of the machine and when in use being provided with a cutter chain 15^a which may be of the usual construction. This cutter bar is supported for 60 pivotal movement by means of a bracket 16 pivotally mounted for normal transverse movement in upper and lower bearings 17, 17^a, formed integrally at the forward end of a swinging auxiliary frame, 18.

Said swinging frame is provided with a rearwardly projecting horizontally disposed stub shaft 20 journaled in bearings 21 and 22 formed integral with the sub-frame 7, thereby permitting bodily pivotal movement 70 of the cutter arm and the swinging frame 18 upon a horizontal axis.

The cutter chain is driven through the following mechanism:

A motor 25 is mounted on the sub-frame 75 7 preferably near the rear end thereof as shown, and has armature shaft 26 at its forward end journaled in the bearing member 22^a. A driving pinion 28 at the forward end of shaft 26 meshes with a spur member 29 80 of cluster gear 30 loosely mounted on the stub shaft 20. The forward member of this cluster gear comprises a bevel gear 31 which engages the bevel gear 32 at the lower end of an upright shaft 33 journaled in a 85 bearing 34 formed in the swinging frame 18. A longitudinal shaft 36 is carried in a similar bearing 37 on the upper end of frame 18 and carries on its rear end a mitre gear 35 which meshes with a similar gear 35^a on the upper end of shaft 33. A bevel gear 38 90 at the forward end of shaft 36 engages a bevel gear 39 on the upper end of a vertically disposed shaft 40. This shaft extends concentrically through the sleeve portion 16^a of 95 the bracket 16 and has a chain sprocket 41 thereon in alignment with the cutter arm 15 in position to drive the cutter chain in the usual manner.

The mechanism for swinging the cutter arm in a horizontal plane in either direction with respect to the mine bottom will now be described. As shown herein a longitudinal shaft 54 has bearing 55 in and extends through the stub shaft 20 and is journaled at its rear end in a fixed support 55. Operative connections from the motor 25 to the shaft 54 are provided through a spur pinion 50 on the shaft 26 and an idler 51 mounted on the bracket 27 which are arranged to mesh at 110

will with spur members 52 and 53 loosely mounted on the shaft 54 and forming the inner members of a sliding and reversing clutch mechanism. Sliding clutch members 56 and 57 feathered on the shaft 54 form the outer members of this mechanism. Said clutch members are preferably interlocked in any usual manner so that only one may become engaged at a time. A worm 60 mounted on the forward end of shaft 54 engages a worm gear 61 at the upper end of a vertical shaft 63. A spur pinion 62 at the lower end of said shaft meshes with spur segment 64 carried concentric with the sleeve 15 member 16^a.

The entire forward portion of the machine, comprising the members 16 and 18, and the cutter arm 15, may be adjusted vertically in either direction with respect to 20 the mine floor in any desired manner. As herein shown manual adjusting means is provided comprising a worm gear segment 65 mounted on the stub shaft 20 and having engagement with a worm 66. This worm is 25 operated by a hand wheel 66^a.

The arrangement is such that the cutter chain will be operable in any permissible position of the cutter arm when pivoted transversely of the machine in the bearings 30 17, 17^a, or when pivoted horizontally by pivotal movement of the swinging frame 18, as just above described.

The sub-frame 7 carrying the entire cutting mechanism is adjustable vertically by 35 means of the following mechanism:

A bevel armature pinion 70 preferably at the rear end of the motor 25 engages a bevel gear 71 mounted on the upper end of a vertical shaft having bearing through a bracket 40 member 73 suitably attached to the motor shell. A bevel gear 74 at the lower end of said shaft meshes with a pair of oppositely disposed bevel gears 75 and 76, loosely mounted on transverse shaft 77 along the 45 rear end of the sub-frame 7, and provided with a reversing clutch mechanism 78 feathered on said shaft in the usual manner to afford a driving connection in reversing directions at will. Two pairs of mitre gears 50 79, 79 are arranged at the corners of the sub-frame 7 to provide a driving connection with the longitudinal shafts 80, 80 along opposite sides of said sub-frame and having pinions 8, 8 keyed thereon which form vertically 55 movable supporting connections with the racks 10, 10 on the upright supports 4, 4 as already described. By means of the reversing clutch 78, it will be seen that the entire cutting mechanism and the sub-frame may 60 be adjusted vertically in either direction under power of the motor 25.

The cutter arm may also be fed to the coal by pivotal movement of the turntable upon which the entire cutter mechanism and motor 65 25 are supported. As shown herein, the

driving means comprises a motor 80 at the rear end of the main frame having driving connection with the turntable through a motor pinion 81, gear 82, shaft 83 worm 84, worm gear 85, shaft 86, gears 87 and 88, shaft 89 and gear 90, the latter named gear being meshed with a toothed periphery 91 of the turntable. The turntable may thus be swung in either direction and at any angle to the base frame so as to cut a kerf in any 70 permissible position of the cutter arm either in a vertical or in a horizontal plane.

The machine may also be used for making a slabbing cut along a face parallel with the mine tracks by swinging the turntable so 80 that the cutter arm projects laterally from the main frame and is locked in this position while the machine is propelled along the tracks parallel to the working face, with the cutter arm maintained in a horizontal position.

Suitable means for propelling the truck may be provided as herein shown including a chain 95 driven by sprocket 96 on one end of shaft 83 and operatively connected thereto 90 through a sliding clutch member 97, said chain 95 being operatively connected to the rear axle through a chain sprocket 98 in the usual manner.

Although I have shown and described one 95 embodiment of my invention, it will be understood that the construction and arrangement of the various parts may be altered without departing from the spirit and scope thereof. Furthermore, I do not wish to be 100 construed as limiting myself to the particular construction illustrated excepting as it may be specifically limited in the appended claims.

I claim as my invention:

1. In a mining machine, the combination of a turntable, a sub-frame vertically adjustable with respect thereto, a swinging frame mounted for pivotal movement on a horizontal axis at one end of said sub-frame, a supporting member carried by said swinging frame adapted for pivotal movement on a vertical axis, a cutter chain sprocket on said supporting member, a motor on said sub-frame, means whereby said motor 110 may actuate said cutter chain sprocket in all permissible positions of said swinging frame and supporting member, means whereby said motor may selectively control certain of the pivotal movements of said swinging frame and supporting member, and other means whereby said motor may selectively control the vertical adjustment of the entire apparatus with respect to the wheeled support.

2. In a mining machine, the combination of a turntable having upright supports thereon, a sub-frame vertically adjustable between said supports, a swinging frame mounted for pivotal movement on a hori- 130

zontal axis on said sub-frame, a supporting member mounted on said swinging frame for pivotal movement on an axis transverse to the axis thereof, a cutter arm rigidly carried by said supporting member, and a motor carried by said sub-frame having operative connections with said supporting member for moving the same about its axis.

3. In a mining machine, the combination of a turntable having upright supports thereon, a sub-frame vertically adjustable between said supports, a swinging frame mounted pivotally on a horizontal axis on said sub-frame, a supporting member carried by said swinging frame for pivotal movement on an axis transverse to the axis thereof, a cutter arm rigidly mounted on said supporting member, a cutter chain sprocket mounted concentric with the axis of said supporting member, a motor carried by said sub-frame having operative connections with said supporting member for moving same about its axis, and other operative connections between said motor and said chain sprocket whereby the latter may be actuated in any permissible position of said cutter arm.

4. In a mining machine, the combination of a turntable having upright supports thereon, a sub-frame vertically adjustable between said supports, a swinging frame mounted pivotally on a horizontal axis on said sub-frame at the forward end thereof, a supporting member carried by said swinging frame for pivotal movement on a vertical axis, a cutter arm rigid with said supporting member, a cutter chain sprocket mounted concentric with the axis of said supporting member, a motor carried by said sub-frame, means at one end of said motor and concentric with the axis of said swinging frame whereby the pivotal movement of said

supporting member may be controlled, operative connections adjacent the same end of and between said motor and said chain sprocket whereby the latter may be actuated in all permissible positions of said cutter arm, and other actuating means concentric with said selective control means and with the axis of said swinging frame whereby the latter may be pivoted.

5. In a mining machine, the combination of a turntable having upright supports thereon, a sub-frame vertically adjustable between said supports, a swinging frame mounted pivotally on a horizontal axis on said sub-frame at the forward end thereof, a supporting member carried by said swinging frame for pivotal movement on a vertical axis, a cutter arm rigid with said supporting member, a cutter chain sprocket mounted concentric with the axis of said supporting member, a motor carried by said sub-frame, means at one end of said motor and concentric with the axis of said swinging frame whereby the pivotal movement of said supporting member may be selectively controlled by said motor, operative connections adjacent the same end of and between said motor and said chain sprocket whereby the latter may be actuated in all permissible positions of said cutter arm, other actuating means concentric with said selective control means and with the axis of said swinging frame whereby the latter may be pivoted, and other means whereby said motor may control the vertical adjustment of said sub-frame at the opposite end of said motor.

Signed at Chicago, in the county of Cook and State of Illinois, this 29th day of December, A. D. 1924.

WALTER S. GRAY.
